PRINTING AND EMBOSsing

Carl A. Flood, Framingham, Mass., assignor to
Dennison Manufacturing Company, Framing-
ham, Mass., a corporation of Massachusetts

Application September 14, 1934, Serial No. 743,966

9 Claims. (Cl. 101—196)

In embossing machines for printing labels, seals and the like in a plurality of colors it is customary to feed a ribbon of paper or sheet metal between a bed and a series of dies lengthwise of the series, the dies being inked with different colors and the strips being fed intermittently by steps equal to the distance between the centers of the dies so that recurrent sections of the strip are recurrently printed in different colors. The sections are cut out of the strip either by one of the dies or by a separate cutter, leaving a skeleton strip of waste material which is fed to a take-up reel, the printed articles being separately fed from the machine.

An outstanding difficulty with machines of this type is accurately to feed the strip by steps which are exactly equal to the distance between centers of dies so that the impressions of the various dies will exactly register with each other. This difficulty is particularly pronounced for the reason that the skeleton strip issuing from the machine, by which the strip is ordinarily pulled through the machine, is so fragile as to be easily stretched, distorted and torn. It has been proposed to feed the strip through the machine on an endless belt but inasmuch as the belt must be relatively soft it stretches too easily to afford an accurate feeding medium.

Objects of the present invention are to provide an embossing machine in which the strip may be fed accurately and upon which the successive impressions may be made in precise registry, and to reduce the waste which has hitherto resulted from inaccurate registration and torn strips.

According to this invention a strip is fed by means located not beyond the dies at the output end of the machine but in advance of the dies at the input end of the machine. The feeding means, which are preferably in the form of pressure rolls, may operate directly on the strip or indirectly on the strip through the medium of an endless belt or both may be fed between the pressure rolls. At the output end of the machine I provide means, preferably in the form of a friction roll or rolls, to hold taut the portion of the strip extending between the dies and the bed of the machine. While the friction means may operate on the strip or belt or both it preferably operates directly only upon the belt and only indirectly on the strip through the medium of the belt, it being understood that the dies impress the embossed sections of the strip more or less into the belt so that they adhere fairly tightly to the belt and that the embossed sections are usually not completely severed from

the skeleton waste portion so that the skeleton also adheres to the belt, the skeleton and the embossed articles being separately stripped from the belt at the delivery end of the machine. The aforesaid friction means at the output end of the machine is preferably driven in synchronism within the feed rolls at the input end of the machine, either at the same speed or preferably at a slightly greater speed. By locating the strip feeding means at the input end of the machine rather than the output end as is customary the feed rolls operate on the strip before it is cut by the dies, thereby permitting the feed means to have a more positive control over the strip. By providing, in advance of the embossing means, feed rolls which have more positive control over the strip than the friction rolls beyond the embossing means, accuracy of registration is increased and waste is reduced.

For the purpose of illustration a concrete embodiment of the invention is shown in the accompanying drawing in which,

Fig. 1 is a diagrammatic elevational view, parts being shown in section and other parts broken away;

Fig. 2 is an enlarged sectional view of the bed of the machine and one of the dies; and

Fig. 3 is a rear view of the drive means.

The particular embodiment of the invention chosen for the purpose of illustration comprises a bed 1, a so-called make-ready 2 mounted on the bed, an endless rubber belt 3, embossing dies 4 mounted on a common support 5 movable up and down by the usual mechanism and an ink roll 7 which rolls under the dies 4 while they are in elevated position as shown in Fig. 1. The strip to be embossed is fed from a feed roll 8 under a roller 9 and thence between the bed and dies, the aforesaid skeleton strip 14 being delivered to a take-up roll 10. Both the belt 3 and the strip 11 to be embossed are fed by means of the pressure rolls 12 which rotate intermittently between successive impressions by the dies 4, each intermittent rotation of the rolls 12 being correlated with the spacing of the dies 4 so that each forward step of the belt and strip is exactly equal to the distance between centers of dies.

The portion of the belt between the bed and the dies is held taut by the friction roll 13 and inasmuch as the strip 11 adheres tightly to the belt as aforesaid the portion of the strip between the bed and dies is likewise held taut by the friction roll 13 acting through the medium of the belt. The waste skeleton 14 is stripped

from the belt at the roll 13, the labels or other embossed articles 15 still adhering to the belt. In order to strip the labels from the belt the latter is pulled around a sharp corner 16, there-
5 by causing the embossed articles to be delivered at 17. After passing the corner 16 the belt passes between rolls 13 and 21 which are held together by a spring 22 acting on roll 21 through arm 23. Thence the belt passes under an ad-
10 justable roll 24 which prevents the belt winding around roll 21 if the belt be sticky.

In order to hold those portions of the belt and strip between the bed and dies with a uniform and constant degree of tautness the friction roll
15 13 is driven in synchronism with the feed rolls 12 by means of a shaft 18 connected to the roll 13 by bevel gears 19 and to the rolls 12 by bevel gears 20, the shaft 18 being rotated intermittently by pawl and ratchet mechanism driven by the
20 rack 6 reciprocating back and forth by suitably timed means. As above indicated, the peripheral velocity of the friction roll 13 is preferably some-
25 what greater than that of the feed rolls 12, this being indicated in exaggerated form in the drawing by showing the roll 13 somewhat larger in diameter than the rolls 12.

It should be understood that the present disclosure is for the purpose of illustration only and that this invention includes all modifications and
30 equivalents which fall within the scope of the appended claims.

I claim:

1. A multicolor printing and embossing machine comprising means including a series of dies for recurrently printing recurrent sections of a strip of material with different colors and cutting out the sections, means in advance of said series of dies for feeding the strip of material to the dies, and means beyond the series of dies for holding taut the portion of the strip between the last two means, said first means having more positive control over the strip than the second means whereby the rate of travel of the strip is determined solely by the first means.

45 2. A multicolor printing and embossing machine comprising means including a series of dies for recurrently printing recurrent sections of a strip of material with different colors and cutting out the sections, means in advance of said series of dies for feeding the strip of material to the dies, means beyond the series of dies for holding taut the portion of the strip between the last two means, and means for causing said feeding means to control the strip more positively than said last means whereby the rate of travel of the strip is determined solely by the feeding means.

3. A multicolor printing and embossing machine comprising means including a series of dies for recurrently printing recurrent sections of a strip of material with different colors and cutting out the sections, driving means in advance of said series of dies for feeding the strip of material to the dies, friction means pulling forwardly on the strip beyond said series, and means for driving the friction means slightly faster than said feeding means, thereby to hold taut the portion of the strip between the driving means and friction means, said driving means having more positive control over the strip than said friction means whereby the rate of travel of the strip is determined solely by the feeding means.

4. A multicolor printing and embossing machine comprising a bed, a series of dies movable toward and from the bed, an endless belt ex-
75 tends between the bed and dies lengthwise of

said series, means in advance of said series for feeding the belt, and means beyond the series for holding taut the portion of the belt between the bed and dies, said first means having more positive control over the belt than the second means whereby the rate of travel of the belt is determined solely by the first means. 5

5. A multicolor printing and embossing machine comprising a bed, a series of dies movable toward and from the bed, an endless belt extending between the bed and dies lengthwise of said series, means in advance of said series for feeding the belt, means beyond the series for holding taut the portion of the belt between the bed and dies, and means for causing said feeding means to 10 control the belt more positively than said last means whereby the rate of travel of the belt is determined solely by the feeding means.

6. A multicolor printing and embossing machine comprising a bed, a series of dies movable toward and from the bed, an endless belt extending between the bed and dies lengthwise of said series, driving means in advance of said series for feeding the belt, friction means pulling forwardly on the belt beyond said series, and means for 20 driving the friction means slightly faster than the feeding means, thereby to hold taut the portion of the belt between the bed and dies, said driving means having more positive control over the strip than said friction means whereby the rate of 25 travel of the strip is determined solely by the feeding means.

7. A multicolor printing and embossing machine comprising a bed, a series of dies movable toward and from the bed, an endless belt extending between the bed and dies lengthwise of said series to form a backing for a strip of material to be embossed, pressure rolls in advance of said series for feeding the belt and strip, and means beyond the series for holding taut those portions of the belt and strip between the bed and dies, said first means having more positive control over the strip than the second means whereby the rate of travel of the strip is determined solely by the first means. 35

8. A multicolor printing and embossing machine comprising a bed, a series of dies movable toward and from the bed, an endless belt extending between the bed and dies lengthwise of said series to form a backing for a strip of material to be embossed, pressure rolls in advance of said series for feeding the belt and strip, means beyond the series for holding taut those portions of the belt and strip between the bed and dies, and means for causing said feeding means to control the strip more positively than said last means whereby the rate of travel of the strip is determined solely by the feeding means. 45

9. A multicolor printing and embossing machine comprising a bed, a series of dies movable toward and from the bed, an endless belt extending between the bed and dies lengthwise of said series to form a backing for a strip of material to be embossed, pressure rolls in advance of said series for feeding the belt and strip, friction means pulling forwardly on the belt beyond said series, and means for driving the friction means slightly faster than the feeding means thereby to hold taut those portions of the belt and strip between the driving means and friction means, said driving means having more positive control over the strip than said friction means whereby the rate of travel of the strip is determined solely by the feeding means. 50
